HOUSEHOLD APPLIANCE CABINET OR SIMILAR ARTICLE

Douglas N. Cabell, Birmingham, Mich., assignor to
Ronson Corporation, Woodbridge, N.J., a corporation
of New Jersey

Filed Aug. 24, 1967, Ser. No. 8,383

Term of patent 14 years

Int. Cl. D6—01

U.S. Cl. D33—19

FIG. 1 is a front perspective of my new design.

FIG. 2 is a rear perspective view thereof.

FIG. 3 is a front perspective view showing details of the interior and also showing a portion of the cabinet top raised.

FIG. 4 is a front view of the cabinet with the door in open position.

FIG. 5 is a sectional view of the cabinet taken along line 5-5 of FIG. 1.

FIG. 6 is a top view thereof.

The dominant features of my design reside in those portions shown in full lines on the drawing.

I claim:

The ornamental design for a household appliance cabinet or similar article, substantially as shown and described.
